L. FRIEDMAN,
GAS PRODUCER.
APPLICATION FILED FEB. 13, 1912.

1,076,823.

Patented Oct. 28, 1913.

UNITED STATES PATENT OFFICE.

LOUIS FRIEDMAN, OF NEW YORK, N. Y.

GAS-PRODUCER.

1,076,323.

Specification of Letters Patent. Patented Oct. 28, 1913.

Application filed February 18, 1912. Serial No. 677,321.

To all whom it may concern:

Be it known that I, LOUIS FRIEDMAN, a citizen of the United States, residing at New York, in the county of New York and State of New York, have invented new and useful Improvements in Gas-Producers, of which the following is a specification.

This invention relates to improvements in gas producers, and its object is to enable the efficient use of low hydrocarbons as the motive fluid of internal combustion engines.

In serving the object stated, the invention provides for the elimination of the unpleasant odor commonly developed when low hydrocarbons are used as motive fluid, and for the production of a permanent gas of high explosive property and which will not be substantially affected by any changes in temperature that may be developed in practice.

The invention comprehends the passage of atomized hydrocarbon, *e. g.* kerosene through a flame whereby certain constituents of the hydrocarbon are consumed and a permanent gas is developed, which, when combined with a proper proportion of air and subjected to compression, is highly explosive and, at the same time, is not substantially affected by the lower temperature of the engine cylinder.

A gas producer in accordance with the invention is illustrated in the accompanying drawings, wherein:

Figure 1 is a vertical central sectional view; and Fig. 2 is a detail horizontal sectional and plan view in the plane of the line 2 of Fig. 1.

Similar characters of reference designate corresponding parts throughout the several views.

The casing into which the motive fluid is admitted and which is connected to the motor suction tube is, for convenience of access, preferably made in upper and lower halves A and B, connected together by bolts C. As shown said casing comprehends concentric shells 1 and 2, the outer shell 1 preferably having a jacket, through which water may circulate. The shell 1 is of generally spherical outline, and connects, at its upper end, with the shell 2. Beyond the connection of the shells 1 and 2 an extension 3 is provided, this extension being, in effect, an axial continuation of the shell 2 and constituting a mixing chamber. The motor suction tube (not shown) is connected to the mixing

chamber 3, and the motive fluid is introduced at the opposite end of the casing and into the shell 2, which is preferably bell-shaped at its lower end, as at 2^a. Centrally of the end 2^a of the shell 2, an upwardly directed nozzle 4, controlled by a needle valve 5, is provided. At one side of the nozzle casing there is an oil connection 6, controlled by a needle valve 7 and at the other side of said nozzle casing there is an air connection 8 controlled by a needle valve 9.

The nozzle 4 is located with relation to a pair of electrodes 10, one of which is connected to a vibrator, whereby an arcing will be set up to ignite the mixture which passes from the nozzle 4. To sustain this ignition, air is admitted into that portion 2^b of the shell 2 which is located immediately above the electrodes 10, such admission of air being provided for by openings 11 in the wall of said shell. The efficient size of the openings 11 may be regulated in any suitable manner. For instance, a sleeve 12 may be provided, which is slidable axially on the portion 2^b and is provided with openings 13 to register or partially register with the openings 11. The sleeve 12 may be connected to a bell crank lever 14, the free arm of which carries an adjustment screw 14 and is pressed inwardly by a spring 15. The screw 14 bears against the outer side of the shell 1 and the spring 15 may be fitted in a lateral post 16 which is attached to the shell 1 and passes loosely through an opening in the free arm of the lever 14.

Beyond the portion 2^b the shell 2 is shaped as a Venturi tube, as at 2^c and incloses a tubular coil 17, through which air circulates. The coil 17 is supplied with air by means of a supply tube 18 which leads from the connection 8; and the upper convolution of said coil is provided with a number of air discharge openings 19. The heated air which issues from the openings 19 mingles with the gas which passes through the Venturi tube portion 2^c, and the mixture of heated air and gas has obtained passes through the upper portion 2^d of the shell 2 to the mixing chamber 3. In the said upper portion 2^d of the shell 2 a throttle valve 20 is provided. The heated air and gas which passes into the mixing chamber 3, therein combines with an additional supply of air which enters the bell-shaped lower end 1^a of the shell 1, and passes upwardly through the space between the shells 1 and 2, passing into the

mixing chamber through openings 21, formed at the upper end of the shell 2. The additional supply of air referred to is really the main supply of air, and it is correctly proportioned by valve means which is subject to the suction influence in the mixing chamber and in the motor suction tube.

The shells 1 and 2 are connected approximately midway of the height of the casing by a web which is formed with a number of openings 21^a through which the air entering between the shells 1 and 2 passes. The openings 21 are controlled by a pair of valve flaps 22. These are of semi-circular outline, and are hingedly connected, as at 23, the hinges 23 including pintles and springs which tend to cause the flaps 22 to seat upon the web in which the openings 21 are formed. The pintles of the hinges 23 are in turn formed as lateral extensions of rods 24 which are slideable in bearings 25 secured to the inner face of the shell 1 and which are forced downwardly by springs 26. Thus the valve flaps 22 are capable of two movements, which may be independent or joint. When the engine is running at low speed, the flaps 22 will not have any pivotal movement, but, maintained in a horizontal plane by the springs of the hinges 23, will move vertically on the rods 24 as an axis. However, when the engine is running at higher speeds, and the suction developed is correspondingly greater, the flaps 22 will move on the hinges 23 as an axis, as indicated by dotted lines, or they may move both on the hinges 23 and on the rods 24, according to the degree of suction developed. It will thus be seen that the valve organization, comprehending the flaps 22, automatically and accurately adjusts itself to the speed of the engine, and the degree of suction developed thereby, and consequently insures a proper proportioning of the air constituent of the gaseous mixture.

In use, air and oil are supplied under pressure through the connections 6 and 8, discharging at the nozzle 4 and passing through the arc developed by the electrodes 10. At such time, the mixture is ignited, the flame being sustained by the air which is admitted through the openings 11 and acting on the mixture which continually passes from the nozzle 4, with chemical effect, producing a permanent gas which is heated and passes from the Venturi portion 2^a and on the outside of the coil 17. The flame at the same time heats the air which is delivered to said coil by the tube 18. The coil 17 and the Venturi portion 2^a are also heated, so that the air in the coil and the gas passing through the Venturi portion ultimately commingle in a highly heated condition. The heat of the Venturi portion 2^a also acts on the air which passes through the space between the shells 1 and

2, efficiently heating this air prior to its passage to the mixing chamber. Within the mixing chamber the air passed by the shell 1 commingles with the air and gas passed by the shell 2, and establishes a mixture of proper proportions to secure good explosive effects. The permanent gas which is evolved by the action of the flame on the mixture passing from the nozzle 4 is not subject to condensation, and will, therefore, not be substantially affected by the lower temperature of the walls of the engine cylinder.

Having fully described my invention, I claim:

1. In a gas producer, a shell subject to the suction of the engine, an oil supply communicating with said shell, electrodes in relation to the oil supply to establish an arc and ignite the mixture passing from the oil supply, a coil within said shell and through which air is caused to circulate, the coil being subject to the heat of the flame of the ignited mixture, and having air discharge openings, and a mixing chamber to which the air from the coil and the gas evolved by the ignition of the mixture passes.

2. In a gas producer, a shell subject to the suction of the engine, an oil supply communicating with said shell, electrodes in relation to the oil supply to establish an arc and ignite the mixture passing from the oil supply, a coil within said shell and through which air is caused to circulate, the coil being subject to the heat of the flame of the ignited mixture and having air discharge openings, a mixing chamber to which the air from the coil and the gas evolved by the ignition of the mixture passes, and means for supplying additional air to the mixing chamber.

3. In a gas producer, a shell subject to the suction of the engine, a second shell in surrounding relation to said first-named shell and connected to the latter at its upper end, an extension of the first shell which forms a mixing chamber, the first shell having openings through which air drawn through the second shell passes to the mixing chamber, an oil supply communicating with the second shell, and electrodes in relation to the oil supply to establish an arc and ignite the mixture passing from the oil supply, the mixing chamber receiving the gas evolved by the ignition of the mixture.

4. In a gas producer, a shell subject to the suction of the engine, a second shell in surrounding relation to said first-named shell and connected to the latter at its upper end, an extension of the first shell which forms a mixing chamber, the first shell having openings through which air drawn through the second shell passes to the mixing chamber, an oil supply communicating with the second shell, electrodes in relation to the oil

supply to establish an arc and ignite the mixture passing from the oil supply, the mixing chamber receiving the gas evolved by the ignition of the mixture, and a coil 5 located in the first shell and through which air is caused to circulate, the coil being subject to the heat of the flame of the ignited mixture and having openings through which the air discharges to mingle with the

10 gas which passes to the mixing chamber.

5. In a gas producer, a shell subject to the suction of the engine, a mixing chamber communicating with one end of said shell, means within said shell for developing a 15 gas which passes to the mixing chamber, a second shell in surrounding relation to the

first shell and in communication with the mixing chamber, the second shell opening to the atmosphere and passing air to the mixing chamber, an annular web bridging 20 the space between the shells and having air openings, and flap valves spring-pressed upon the web and mounted for pivotal movement and also for vertical rectilinear movement.
